United States Patent Office

Des. 213,360
Patented Feb. 25, 1969

213,360

CART

Delmar H. McClure, 9051 SE. 55th Ave.,
Portland, Oreg. 97206

Filed July 1, 1968, Ser. No. 12,579

Term of patent 14 years

U.S. Cl. D14—3
Int. Cl. D12—02

Fig. 1.

Fig. 3.

Fig. 2.

Fig. 4.

Fig. 5.

Fig. 6.

FIG. 1 is a perspective view illustrating the cart, with panels therein mounted to form shelves.

FIG. 2 is an enlarged end elevational view of the cart, taken from the left side thereof in FIG. 1.

FIG. 3 is a rear elevation of the cart.

FIG. 4 is a perspective view of the cart with panels therein installed to form a front wall.

FIG. 5 is a perspective view illustrating the cart with one panel therein installed to form a shelf and another panel installed to form a front wall.

FIG. 6 is a perspective view of the cart employing a single panel installed to form a front wall.

I claim:

The ornamental design for a cart, as shown and described.
